UNITED STATES PATENT OFFICE.

FREDERICK C. SUTTER, OF SWISSVALE, PENNSYLVANIA.

DESIGN FOR A TRANSFORMER-CASE.

SPECIFICATION forming part of Design No. 29,410, dated September 27, 1898.

Application filed August 6, 1898. Serial No. 687,992. Term of patent 14 years.

To all whom it may concern:

Be it known that I, FREDERICK C. SUTTER, a citizen of the United States of America, and a resident of Swissvale, county of Allegheny, 5 and State of Pennsylvania, have invented and produced a new and original Design for Transformer-Cases, of which the following is a specification.

Referring to the accompanying drawings, 10 which make part of this specification, Figure 1 is a perspective showing the front, left side, and top of my design, while Fig. 2 is also a perspective, but showing the rear, right side, and top of said design; and Fig. 3 is a plan 15 view of my design.

My invention relates to a design for a case for electrical transformers, and its material features are as shown in the drawings.

1 is the plane-sided body portion, with 20 rounded edges 2, tapering slightly from the top.

3 is the lower body portion, of greater taper than portion 1 and of inverted truncated pyramidal form; also, with rounded edges 2^a, 25 the juncture of portions 1 and 3 being also rounded.

4 is a portion with vertical sides, also with rounded corners beneath portion 3. Around the top of portion 1 is a collar-like portion 5, 30 likewise with rounded edges and corners. At the sides of body 1 collar 5 is provided with slotted depending hook-like projections 6 6. On the upper part of the front of body 1, near the corners, are two double projections from 35 collar 5, portions 7 7 giving a fluted appearance to the portions thus formed.

8 is a partly-cylindrical portion integral with portion 3.

At the rear corners of collar 5 are rounded 40 lateral projections 9 9, and from the rear of

collar 5 are two projections 10 10, rectangular at their lower extremities and for some distance above, but finally tapering in a compound curve into said collar at the top.

11 is the top portion of the case, having 45 rounded corners and beaded edge 12. At its rear corners portion 11 is provided with projections 13 13, of similar plan contour to projections 9 9. At its front portion 11 is provided with fluted projections 14 14. 15 15 50 are cylindrical portions beneath portions 9 9. At its sides portion 11 is provided with laterally-tapering projections 16 16, and 17 17 are polygonal portions surmounting projections 16 16. Approximately in the center of portion 11 is raised portion 18, provided with beveled sides and rounded corners, the surface of said portion 11 sloping from a line within its edge slightly to said raised portion from its four sides in plane surfaces. 55

19 19 are projections from the rear of portion 1, near its lower extremity, rectangular at their bases and for some distance above, and finally tapering upward in a compound curve into portion 1. Projections 10 10 and 19 19 65 are provided with U-shaped slots open at the lower ends 20 20.

21 21 are cylindrical portions beneath portions 7 7, and 22 22 are cylindrical portions above portions 9 9. 70

Having described my invention, what I wish to claim is—

The design for a transformer-case, as herein shown and described.

Signed by me, at Pittsburg, Pennsylvania, 75 this 18th day of June, 1898.

FREDERICK C. SUTTER.
